ICE CUBE MAKER

**Kenneth W. Mackenzie, Hudson, Wis., assignor to
United Refrigerator Company, Hudson, Wis., a
corporation of Minnesota**

Application January 22, 1948, Serial No. 143,975

Term of patent 14 years

(Cl. D67—3)

To all whom it may concern:

Be it known that I, Kenneth W. Mackenzie, a citizen of the United States, residing at 1111 Ninth Street, city of Hudson, county of Saint Croix, State of Wisconsin, have invented a new, original, and ornamental Design for Ice Cube Maker, of which the following is a description, reference being had to the accompanying drawings, forming part thereof.

Fig. 1 is a view in front elevation of an ice cube maker showing my new design;

Fig. 2 is a view in side elevation of the same;

Fig. 3 is a view in rear elevation of the same; and

Fig. 4 is a plan view of the same.

The opposite side of the ice cube maker from that shown in Fig. 2 is substantially like the side shown.

I claim:

The ornamental design for an ice cube maker, substantially as shown and described.

KENNETH W. MACKENZIE.
